UNITED STATES PATENT OFFICE.

LOUIS W. RICE, OF NEW YORK, N. Y., ASSIGNOR TO BERNARD RICE'S SONS, INC., OF NEW YORK, N. Y., A CORPORATION OF NEW YORK.

DESIGN FOR A PITCHER OR LIKE ARTICLE.

Application filed March 23, 1928. Serial No. 25,979. Term of patent 7 years.

To all whom it may concern:

Be it known that I, LOUIS W. RICE, a citizen of the United States, residing at 325 Fifth Avenue, New York city, in the county of New York, and State of New York, have invented a new, original, and ornamental Design for a Pitcher or like article, of which the following is a specification, reference being had to the accompanying drawing, forming part thereof.

The figure is an elevation of a pitcher or like article showing my new design. The characteristic feature of the design is the handle.

I claim:

The ornamental design for a pitcher or like article, as shown and described.

LOUIS W. RICE.
